DESIGN FOR A TABLE

Bernard G. Zolot, Philadelphia, Pa.

Application July 22, 1947, Serial No. 140,441

Term of patent 3½ years

(Cl. D33—14)

To all whom it may concern:

Be it known that I, Bernard G. Zolot, a citizen of the United States, residing at Philadelphia, in the county of Philadelphia, State of Pennsylvania, have invented a new, original, and ornamental Design for Tables, of which the following is a specification, reference being had to the accompanying drawing, forming part thereof.

Figure 1 is a perspective view of a table embodying the design of my invention; and Figure 2 is a bottom view thereof.

I claim:

The ornamental design for a table, substantially as shown.

BERNARD ZOLOT.
